UNITED STATES PATENT OFFICE.

HERMAN PLAUT, OF NEW YORK, N. Y., ASSIGNOR TO L. PLAUT & COMPANY, INCORPORATED, OF NEW YORK, N. Y., A CORPORATION OF NEW YORK.

LIGHTING FIXTURE.

Application filed July 22, 1927. Serial No. 207,624.

My invention relates to the art of illumination, and particularly to devices adapted to receive and position light sources and surround them with reflecting and diffusing means to cause the light rays to be delivered in a certain definite manner.

My object is to construct a fixture carrying two light sources, surrounded by diffusing means combined with reflecting means, to direct the rays from the light sources in different directions and yet cause the two light sources to function together for producing the general effect desired in the illumination.

My invention consists of certain detailed construction hereinafter set forth, pointed out in my claim, and illustrated in the accompanying drawings, in which—

Fig. 1 shows a side elevation view of my fixture, part of the globe being broken away to reveal the inner construction; and

Fig. 2 shows, in reduced scale, a section taken on line 2—2 of Fig. 1.

Similar reference numerals refer to similar parts throughout the entire description.

Referring to the accompanying drawings, I employ a globe holder 10, attached, in the ordinary manner, to a chain hanger 11, or a canopy. In the canopy is mounted an electric light socket 12, supplied with proper current-carrying wires (not shown). The upper portion 13 of the globe, preferably constructed of diffusion glass, is secured to the globe holder 10 in the usual manner. A metal ring 14 is secured by straps 15 to a hickey 16 in the canopy 10, as shown. This metal ring 14 engages the lower edge of the globe portion 13, and is provided with a circumferential flange 17, within which the lip of the lower portion 21 of the globe rests. A metal strap 18 extends across the ring 14, and is orificed to support a socket 19 which depends therefrom. Supply wires 20 conduct current to this socket 19, the said wires 20 obviously passing upwardly and through the hickey 16. The lower portion 21 of my globe, also preferably formed of diffusion glass, is held in position by the flange 17 in any ordinary manner, such as is illustrated at 22, and shown in detail in Fig. 1. Electric light bulbs 23 and 24 are mounted in the sockets 12 and 19 respectively. A concavo-convex reflector 25 is secured to the metal ring 14 and centrally positioned with relation to the light sources 23 and 24. The upper face of the reflector 25 will receive

rays from the light source 23 and direct them upwardly, and the lower face of said reflector will receive rays from the light source 24 and direct them downwardly and outwardly. It is very important that the light sources 23 and 24 be in proper vertical alignment, so that the common reflector 25 may function to provide an even and regular distribution of the rays from each source.

In constructing lighting fixtures, the problem of the illumination engineer is to utilize the light so that the most effective distribution for the purpose in mind may be produced. My fixture is designed to give a more or less concentrated delivery of diffused light upon the working plane from the lower light source, and a full distribution of light over the ceiling and in the corners of the room from the upper light source. By properly aligning my two light sources, and using a divided globe with a concavo-convex reflector mounted between the globe portions to direct the light, I obtain, from two independent light sources designed to function together for general room illumination, a most satisfactory distribution of light.

In my drawings I have illustrated a preferred construction, but it is obvious this is only one illustration of how my invention may be adapted for use, and I do not want to be limited in the scope of my protection, except as set forth in the appended claim.

Having described my invention, what I regard as new, and desire to secure by United States Letters Patent, is:

In a lighting fixture, the combination, with a canopy, of an electric lamp socket depending therefrom, an electric lamp mounted therein, a diffusing glass shade detachably secured to said canopy and enclosing said lamp, a reflector closing the bottom of said shade, all of the rays from said lamp not passing directly through said shade being redirected by said reflector, whereby the ceiling and upper corners of the room are illuminated, there being a central opening in said reflector, an electric lamp socket depending therefrom, a lamp in said socket, a glass bowl enclosing said lamp and reflector detachably secured to the glass shade, the lower surface of said reflector reflecting to the working plane all the rays from said lamp not passing directly through the glass.

HERMAN PLAUT.
